UNITED STATES PATENT OFFICE.

GEORGE C. LYNCH, OF NEW YORK, N. Y.

DESIGN FOR A LAMP-SHADE.

47,646.

Specification for Design.

Patented July 27, 1915.

Application filed March 19, 1915. Serial No. 15,628. Term of patent 3½ years.

To all whom it may concern:

Be it known that I, GEORGE C. LYNCH, a citizen of the United States, and a resident of the city of New York, borough of Manhattan, in the county and State of New York, have invented a new, original, and ornamental Design for Lamp-Shades.

The figure is a side elevation of a shade for a lamp, showing my new design, wherein the principal feature consists in providing a silhouette design on a ground which is translucent to permit the light of a lamp

to pass therethrough, for throwing the design into sharply distinct contrast, said ground being of a color approximating by day the contrast resulting at night by illuminating said ground.

I claim:

The ornamental design for lamp shade, as shown and described.

GEORGE C. LYNCH.
